By his Attorney Dr. Adams

UNITED STATES PATENT OFFICE.

EDWARD FIELD SANFORD, JR., OF NEW YORK, N. Y., ASSIGNOR TO RADIO CORPORATION OF AMERICA, A CORPORATION OF DELAWARE.

DESIGN FOR A CABINET FOR SOUND-REPRODUCING MACHINE.

Application filed December 4, 1922. Serial No. 4,470. Term of patent 14 years.

To all whom it may concern:

Be it known that I, EDWARD F. SANFORD, Jr., a citizen of the United States, and a resident of New York city, in the county of New York and State of New York, have invented a new, original, and ornamental Design for Cabinet for Sound-Reproducing Machines, of which the following is a specification, reference being had to the accompanying drawing, forming part thereof.

The single figure of the drawing shows the cabinet in perspective.

I claim:

The ornamental design for a cabinet for sound reproducing machine as shown.

EDWARD FIELD SANFORD, JR.
